UNITED STATES PATENT OFFICE.

BENJAMIN EVERETT GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

1,327,383.

Specification of Letters Patent.

Patented Jan. 6, 1920.

Application filed May 26, 1919. Serial No. 299,931.

To all whom it may concern:

Be it known that I, BENJAMIN EVERETT GETCHELL, a citizen of the United States of America, residing at Plainville, Connecticut, have invented a new and useful Electric Switch, of which the following is a specification.

The present invention has reference to low voltage switch release mechanism, and the objects of the invention are to provide simple and practical switch release mechanism which when so desired, can be tripped manually and entirely independently of the automatic control.

Briefly, the invention resides in the provision of a push button or other conveniently operable device which can be operated to mechanically trip the switch holding latch independently of the connection between the controlling electromagnet and the latch mechanism. This construction makes it possible to inclose the electro-magnetic trip mechanism within a suitable protective casing, and to make the push button or other actuating device the only exposed portion of the apparatus. This also makes it possible to directly operate the trip in case the electro-magnetic mechanism should "stick" and hence fail to trip the latch when it should.

Other advantages and features of the invention will become apparent as the specification proceeds.

In the accompanying drawing, I have illustrated the invention embodied in a practical commercial form, but would have it understood that the form of the structure may be modified without departure from the spirit and scope of the invention.

In this drawing:

Figure 1, is a side elevation of the invention as applied to an inclosed or "safety" switch, only a portion of the switch casing appearing in this view.

Fig. 2, is a sectional view of the mechanism taken substantially on the plane of the line 2-2 of Fig 1.

Fig. 3, is a fragmentary view illustrating the operation of the device.

5 designates a portion of the switch box or casing within which the switch mechanism is mounted and 6 designates the latch operating handle which is connected with and

may be considered as forming a part of 55 the movable element of the switch.

The latch mechanism comprises a latch lever 7 pivoted at 8 and provided with a hook 9 at its forward end for holding engagement with a pin 10 on the switch 60 lever 6.

The latch lever is secured in holding engagement with the movable switch element by a trip lever 11 pivoted at 12 and provided with a shoulder 13 forming a rest or 65 stop engaging the rearward end of the trip lever (see Figs. 1 and 2). A relatively light spring 14 connected with the trip lever rocks said trip lever over into position to bring the shoulder 13 thereon into supporting 70 position beneath the rearward end of the trip lever and said latter end of the trip lever is acted upon by a spring 15 which rocks the latch lever out of its holding position when the rearward end thereof is 75 freed from engagement with the shoulder on the trip lever (see Fig. 3).

The automatic release of the switch is accomplished by the falling of the solenoid core 16, provided with a head 17 overstanding an angularly projecting arm 18 on the trip lever, said core being supported, when the switch is closed, by the solenoid winding 19 and adapted to fall when said winding is deenergized or when the voltage drops to 85 a predetermined point and to thereupon operate the trip lever.

The switch may be released independently of the automatic control by means of a push button 20 having a pointed or cam-faced 90 lower end 21 adapted to engage a shoulder or cam surface 22 on the trip lever. This push button is normally sustained by a spring 23 and it will be clear from Figs. 2 and 3 that when the same is depressed, 95 the trip lever will be rocked in a direction to carry the supporting shoulder 13 from beneath the rearward end of the latch lever, whereupon the latch lever will be tripped from holding engagement with the movable 100 switch element.

The solenoid 19 and core 16, constituting the electro-magnetic trip mechanism, are protected by a casing 24 which preferably covers the top of the solenoid to prevent 105 access of dust, etc., to the movable core. The push button is shown extending through the wall of this casing and it will be ob-

served that the head of this push button is in fact the only part of the trip mechanism which is exposed, the other parts being amply protected within the casing referred to.

With this invention it will be seen that it is possible to trip the switch by mechanically releasing the latch at any time and entirely independent of the automatic control exercised by the electro-magnetic trip mechanism. This mechanical tripping of the latch mechanism also makes it possible to release the switch in case the armature of the magnet should become caught, or the parts should "stick" or fail to operate properly.

I claim:

1. The combination with the movable element of an electric switch, of a latch lever for holding said movable switch element in one position, a trip lever for securing the latch lever in holding position, an electro-magnet for freeing the trip lever from holding engagement with the latch lever, said trip lever having an arm for engagement with the latch lever and provided with a cam shoulder, and an operating member for said trip lever engaging said cam shoulder.

2. In an electric switch, a pivoted operating handle, a spring actuated latch pivoted on an axis parallel to the axis of the operating lever adapted to engage and hold the operating lever, a spring actuated trip lever pivoted on an axis at right angles to the axis of the latch, electro-magnetically operated means for moving the trip lever, and a spring pressed member independent of the electro-magnetically operated means adapted to operate said trip lever and having an exposed manually operable push button.

3. In an electric switch, an exposed pivoted operating lever, a pivoted latch adapted to engage said lever, a trip lever for engaging said latch, electro-magnetically operated means for moving said trip lever, a housing inclosing said trip lever, said electro-magnetically operated means and part of said latch, and an exposed push button having a shank extending into said housing for operating said trip lever and independent of said electro-magnetically operated means.

4. In an electric switch, a box for the switch mechanism, an external operating handle, a latch external to the box for engaging said handle, a trip lever external to the box for holding said latch, electro-magnetically operated means external to the box for mov-

ing said lever, a manually operable push button for moving said trip lever, and a housing external to said box and inclosing said electro-magnetically operated means, said trip lever and a part of said latch.

5. In an electric switch, an operating handle, a latch for engaging said handle, a trip lever for engaging said latch, electro-magnetically operated means including a longitudinally movable member for engaging said trip lever, and a spring pressed manually operable push button movable on an axis parallel to said longitudinally movable part but independent thereof for operating said trip lever.

6. In an electric switch, an operating handle having a spring tending to move it in one direction, a spring actuated latch for engaging said handle, a spring actuated trip lever for engaging said latch, an electro-magnetically operated device for operating said trip lever, and a spring pressed manually operable device independent thereof for operating said trip lever.

7. In an electric switch, an operating handle, a latch, a trip lever, electro-magnetically operated means for moving said trip lever, said trip lever having an arm with one end bent at an angle thereto, and a push button having a conical member for engaging the end of said arm.

8. In an electric switch, an operating handle, a pivoted latch, a trip lever pivoted on an axis at right angles to said latch, automatically operable releasing means for said trip lever, said trip lever having an arm with a bearing shoulder and a manually operable push button having a conical bearing surface for engagement with said bearing shoulder.

9. In an electric switch, an operating handle, a spring actuated latch, a spring actuated trip lever, automatic means for operating said trip lever, said trip lever having an arm provided with an extended bearing surface and a manually operable push button having a bearing face adapted to coact with said extended bearing surface.

10. In an electric switch, an operating handle, a spring actuated latch, a spring actuated trip lever, automatically operable means for moving said trip lever, a spring pressed manually operable push button having an inclined face for engaging a portion of said trip lever.

BENJAMIN EVERETT GETCHELL.
